[57] CLAIM

The ornamental design for an egg ramp for life cycle poultry cage, as shown and described.

DESCRIPTION

FIG. 1 is a perspective view of an egg ramp for life cycle poultry cage showing my new design.

FIG. 2 is an enlarged scale right side elevational view, an intermediate portion being broken away for ease of illustration.

FIG. 3 is a top plan view thereof, intermediate portions broken away for ease of illustration.

FIG. 4 is an enlarged scale fragmentary perspective view of the left front corner of the egg ramp for life cycle poultry cage.

FIG 3

FIG 2
